UNITED STATES PATENT OFFICE.

CONSTANTIN VON HANNEKEN, OF BERLIN, GERMANY.

AUTOMATIC ORDNANCE OF LARGE CALIBER.

SPECIFICATION forming part of Letters Patent No. 668,835, dated February 26, 1901.

Application filed January 13, 1899. Serial No. 702,061. (No model.)

To all whom it may concern:

Be it known that I, CONSTANTIN VON HANNEKEN, a subject of the King of Prussia, German Emperor, residing at Berlin, in the Kingdom of Prussia, Germany, have invented certain new and useful Improvements in or Relating to Automatic Ordnance of Large Caliber, (for which I have applied for a patent in Germany, filed June 27, 1898; in Austria, filed July 11, 1898; in England, filed July 2, 1898; in Switzerland, filed July 11, 1898; in France, filed June 20, 1898; in Belgium, filed June 27, 1898; in Sweden, filed June 29, 1898, and in Italy, filed July 1, 1898,) of which the following is a specification.

This invention relates to a further improvement in the construction of automatic ordnance of large caliber making the object of my application, Serial No. 682,063, filed May 28, 1898.

Reference is to be had to the accompanying drawings, in which—

Figure 1 is a side view of the single gun in the loading position before the beginning of the loading operation, the side wall of the gun-carriage covering the arrangement of the recoil and loading device being omitted. Fig. 2 is an outer side view of the gun in the loading position after loading. Fig. 3 is a corresponding rear view. Fig. 4 is a side view corresponding to Fig. 2, the gun being in the firing position. Fig. 5 is a plan view of the arrangement, the gun being shown in dotted lines. Fig. 6 is a longitudinal section through the recoil and loading cylinders. Fig. 7 is a detail view of the recoil and loading pistons. Figs. 8 to 10 are three sectional plans through the said cylinders through lines $x-x$, $y-y$, and $z-z$, respectively, of Fig. 6. Fig. 11 is a rear view of the breech. Figs. 12 and 13 are side views of the breech-block, with the locking devices in section, the breech-block being shown in its raised and lowered position. Fig. 14 is a transverse section of the same. Figs. 15 and 16 are longitudinal sections corresponding to Figs. 12 and 13. Fig. 17 is a plan view of the breech, the block being removed. Fig. 18 is a section through the gun-barrel and the pointing arrangement in the direction of the axis of the pointing-trunnions. Fig. 19 is an internal view of the sliding rail for the pointing-trunnions of the gun, and

Fig. 20 is a diagrammatic view of the motion of the breech-block.

The substructure for the single gun is shown in Figs. 1 to 4. To the platform is secured a fixed frame receiving the accumulator as well as the bearings of the lever systems by which the recoil-power is transmitted to the several mechanisms. The frame A consists of two strong side metal plates firmly connected with each other by means of suitable transoms forming front and rear stops a . The gun is supported on a strong lever B, pivoted on a shaft b , journaled on the lower part of the frame-box. The upper part of the lever B is forked, having in its fork bearings for the trunnions, so that the gun can swing in an arc around the shaft b . The movement of the lever B is limited by the stops a . Behind the lever B is arranged the casing C of the recoil and loading cylinders, pivoted at e in the frame A and having the head c^2 of the plunger c entering a recess of the lever B and jointed to it by a pin c' . Below c' there is screwed into the right-hand side of the lever B a round striking-stud b' , having a quadrant cut out on its upper side, Fig. 1, so that the pawl t can engage therein. This pawl is pivoted on a shaft journaled in the frame and projecting on one side out of the box of the frame, carrying on its projecting part the pressure-arm t' . On the same side of the gun there is on the shaft b of the lever B a sleeve extending on both sides of the corresponding wall of the frame-box. Within the frame-box a lever P is fixed on this sleeve and outside the right wall of the frame the lever P' . The inner lever P is in connection with the loading-piston, and the outer one has its upper end connected by the rod r to the loading device L, which is constructed as follows: Through N is raised by the thrust of the rod r and lowered by its pulling action. As shown, the loading device L consists of a trough N , serving to receive the cartridges and supported in links by two levers $M M'$. These levers are carried by shafts $w w'$, supported in the wall A and connected with each other by means of the crank-arms and of the push-rod $Z Z' Z''$ and by the rod r with the lever P' , actuating the loading mechanism. The rear tubular part of the trough carries the slotted rammer-piston actuated by the rammer-lever O.

The lever O swings on a projection N' of the trough and is turned forward at the time the trough moves upward as it catches with a nose O' behind a stop on the shaft w , whereupon the cartridge is pushed in.

The recoil and loading cylinders, Figs. 6 to 10.—For effecting the loading of the gun and its return to firing position I have devised a new arrangement, shown in cross-section on an enlarged scale in Fig. 6. It consists of a strong double cylinder with two bores of different diameters and is pivoted at e to the frame. In the large bore moves the recoil-plunger c , having at its rear end a concave washer and having its front end connected at c' to the lever B . In the small bore is a piston d , the rod d' of which has a slotted head, through which passes loosely to slide therein the lever P , swinging on the shaft of the lever B and actuating the loading device. Below the piston c of the cylinder there is formed a space f , between which and the cylinder is a valve g , which opens during the descent of the piston c , but closes when the downstroke is finished. The air compressed by the piston is forced into the space f . From f a passage h in the wall of the casing leads upward and opens at certain points into the bores, into the larger bore at i , where the washer of the plunger c when it is quite down closes said passage i , and into the smaller bore higher at k , which is above the piston d when it is fully out. The supply of air under pressure into this passage h can be shut off by a valve l , the stem of which passes through the bottom of the cylinder-body and is connected to the starting-lever m , by the movements of which the passage h is closed or opened. Besides the ports i and k of the passage h there is a direct communication n between the two cylinder-bores. Three sectional plans, Figs. 8, 9, and 10, show the communications between the cylinders looking down. The communication n is controlled by a special valve in such a manner that the air under pressure or the liquid in the smaller cylinder passes to the large cylinder when the piston d is below the mouth of n , and the valve in the passage n prevents flow from the large cylinder to the small cylinder, Fig. 10. Between the plunger c and the piston-rod d' there is a connection, such as shown in plan in Fig. 7. On the head of the plunger c a tappet c' projects toward the piston-rod d' , and when the piston advances bears on a corresponding tappet of the piston-rod d' , so that the piston d moves outward along with the plunger c . The plungers work in such a manner that after the valve l is opened by means of lever m the working fluid can only flow through the upper passage k over piston d in its highest position and drive this piston back, so that the loading mechanism is actuated. When piston d has been forced back into its lowest position, the passage n , connecting both cylinders, is free. The fluid passes from the piston d under the plunger c , which is in its

lowest position, until port i becomes uncovered the compressed working fluid flows through the shortest path under plunger c . In the meantime plunger c has, by means of its stop c^0 , raised along with itself piston-rod d' , and the passage n is again closed by the ascending piston d as soon as opening i is uncovered.

Breech-closure, Figs. 11 to 17.—The gun is shown with a vertical breech-closure having an ejector device, Fig. 20, which is opened and closed by means of bent levers 12 11 13, supported in the breech-piece. On both sides of the breech-piece swing the curved rails 14 on pivots 15 of the breech. The pivots, Fig. 11, pass through a bore 17 in the curved rail 14 and aline with the angle 13 of the levers 11 12 13. There is arranged in the lower part of the curved rail a guide-slot 18. The radius of this slot is equal to the distance between the trunnion and the pivot of suspension. The length of the slot corresponds to the desired angular movement of the gun. A strong bolt 19 passes through the walls of the lower carriage and through the slot 18. During the inward and the recoil motion of the gun the curved rails 14 must make a corresponding swinging movement. Each curved rail constitutes, therefore, a lever of the second kind suspended on pivot 15 and the two pivots of application of which are situated at the bolt 19 of the lower carriage and in the bore 17, into which engage the pivots 16 of the closure-lever. The position of the pivot 15 is altered at each inward and recoil motion of the gun, while the bolt 19 is stationary. An angular stroke of the curved rail thus takes place, wherefrom results a corresponding angular motion of the bore 17 of the rail. This angular motion is of such an extent that it corresponds to that stroke of the bent levers 12 11 13 which is necessary for opening and closing the breech. This is clearly explained by the two positions of the breech-block shown in Fig. 20. Owing to the form of the radial slot of the curved rail 14, the breech of the gun when it has returned into the firing position is closed in any vertical position. When the gun has returned into the loading position, the complete opening of the breech takes places in only one position, determined by the pointing device, and in the drawings this is the horizontal position.

The closure is shown in Figs. 11 to 17 of the accompanying drawings. As shown in the longitudinal section, Figs. 15 and 16, the closure contains the hammer o , suspended so as to swing on an upper pivot o' and strike with its point o^2 through an opening in the fore-block face under the action of the spring o^3 against the priming-cap of the cartridge as soon as the closure is closed. A pressure-bolt p passes above the hammer-point transversely through the block, and outside on the block-cheeks (see Figs. 12 and 13) bent pressure-arms p' , riveted to the bolt, swing

also on the pivot o' of the hammer, which projects to the outside. In the slide-faces of the breech of the gun, serving to guide the closure, there are arranged, as seen in the plan, Fig. 17, on each side, two tappets p^2 , dotted in Figs. 12 and 13, and between these the pressure-arms p' , actuating the hammer o , are suspended, so that owing to their peculiar shape they are moved backward when the closure is opened, Fig. 12, and moved forward when the closure is closed, Fig. 13. Thus when the closure is opened the hammer is forced back with certainty by the bolt p compressing the spring o^3 . When the closure is quite opened, the nose o^4 slides over a sear s , urged forward by a small spring. In lowering the closure the arms p' , Fig. 13, again swing forward, taking with them the bolt p . The hammer o , however, is held by the engagement of the nose o^4 with the sear s , Fig. 15. The sear s is provided outside with an aperture having a cam-face s' , which as soon as the breech is completely closed slides down over a cam-lug s^2 , which is secured to the rear part of the breech, so that when the closure is complete the sear s is drawn back, releasing the lever-nose o^4 , so that, as shown in Fig. 16, the hammer is suddenly driven forward.

Stop device.—With the closure a stop device is combined in such a manner that it performs two functions: First, it prevents the cartridge in the gun from sliding backward, which might occur owing to the inertia of the cartridge when the gun is run out, and, secondly, it stops the forward movement of the gun when the cartridge has not been completely seated in its chamber. In order to attain particularly this latter object, the following circumstance has been utilized in constructing the stop device. The breech-block is drawn downward only by the motion of the gun returning to battery. If owing to a defective loading the cartridge does not become completely seated in its chamber, the gun would be brought into its firing position with the breech-closure open. It must therefore be prevented that the gun should move into its firing position when the breech is not absolutely closed, and this is obtained by stopping the disengaged recoil and loading device, which is in its inner position, and consequently the motion of all parts. Such a stopping is effected immediately when the breech-block does not reach its end position in proper time by the peculiar double-lever transmission between the curved rail 14 and the closure-lever 12 11 13, Fig. 20. Any jamming of the breech-closure hinders by the pressure any further motion of the levers and, reacting, renders the recoil and loading device inactive, owing to the position of the lever-arms relatively to each other. For this purpose there is arranged in a bore of the rear part of the breech, Figs. 12 and 13, a bolt 1, which is urged by a spring into a hole in the closure-block when the closure is quite opened.

The bolt 1 has outside an aperture 2, into which can enter the tongue 4 of a pawl 3. The right end, Fig. 17, of this pawl has a nose 5 under the control of a stop 6 as soon as the pawl 3 moves, so that its tongue 4 withdraws the bolt 1 from the recess of the closure. This takes place, Figs. 12 and 15, as soon as the lever O of the loading mechanism has finished its forward motion, effecting the complete introduction of the cartridge into the chamber of the gun, the lever then striking against the pawl 3. In order to prevent the cartridge from sliding back, there is arranged, Fig. 15, below the hammer in the closure-block a vertically-swinging lever 7, urged downward by a spring, so that its front end comes behind the upper edge of the cartridge bottom as soon as a catch behind the bolt is disengaged. This is effected by the pressure of the pin 8, Figs. 15 and 17, against which the lever O strikes. This pin 8 passes through a slot of the pawl 3, and as soon as the lever O when the loading is completed strikes against it the bolt 1 is withdrawn and the lever 7 is at the same time disengaged. When the breech-block is lowered, the lever 7 meets a stop-screw 9 and is turned to the position shown in Fig. 16 out of the way when after the discharge of the gun the empty cartridge is to be ejected. The catch 6 is also moved by engagement with the sear s when the breech is closed, disengaging the pawl 3, so that the bolt 1 can again enter the hole of the closure when the breech is again opened.

Pointing device.—The pointing device shown on the gun in Figs. 1 to 5 is more fully explained on reference to the cross-section, Fig. 18, and its vertical section, Fig. 19. Two slide-rails u are arranged on both sides of the gun, their open sides facing each other, and are pivoted at v' in bracket-plates v , bolted to the fore part of the frame A. In the slide-rails u when the gun moves slide the pointing-pivots R, projecting from the gun, and below the slide-rails there are fixed segments S, the teeth of which gear with two toothed wheels S' on a shaft q , mounted in bearings Q in front of the head of the frame A and turned by a hand-crank, or it might be by a motor and suitable gear.

Working of the single gun.—The single gun is worked in the following manner: The gun is, according to Fig. 1, in the loading position before the beginning of the loading operation. The cylinder c is filled with compressed air or liquid, the cartridge-trough N is lowered, and the closure is opened for receiving a cartridge. A cartridge is placed by hand in the loading-trough. By reversing the lever m , Fig. 6, the valve l is opened and air under pressure flows from the collector f through the channel h , above the piston d , into the cylinder, forcing back the piston d . The piston-rod d' takes with it the lever P on the sleeve of the shaft b , and lever P' , following this backward movement, transmits it by the rod r to the loading mechanism, which is

caused to introduce the cartridge into the gun. When the lever P' terminates its back stroke, it presses against the arm t' of the pawl, releasing it, Fig. 2. At the same time the loading-lever O presses upon the head of pin 8 and unlocks the closure. After the loading has been completed and pawl t released by arm t' the piston d , having been forced backward, passes beyond the passage n , and the fluid under pressure flows from the small cylinder into the main cylinder below the piston c , Fig. 10. This piston is immediately forced forward and bears with its tappet c^0 , Fig. 6, against the corresponding tappet of the piston-rod d' , taking with it the piston d , and so moving the levers P and P' , so that the cartridge-trough is lowered again backward by rod r and cranks z . In its forward movement the piston d shuts off gradually the inlet-opening to n , Figs. 6 and 7; but before the closure is quite completed the piston c has moved forward so far as to open the communication i between the passage h and the large cylinder. The pressure in the space f is communicated through the opening i to the cylinder and terminates the forward movement of the piston c . In the movement of the piston c the lever B , connected therewith, is moved forward and the gun is advanced to the firing position, with the elevation determined by the pointing device. Immediately afterward, after the closure has been completely lowered, the cartridge is fired. By the recoil the lever B is then turned backward and the piston c is forced again into its cylinder. The pawl t catches behind the recess of the bolt b' , so that the gun is stopped in the loading position. The air compressed in the cylinder of the piston is forced through the valve g into the space f , where it receives its initial pressure. It passes then through the valve l , left open, into the passage h , and by actuating the piston d in the small cylinder starts a new loading operation and the subsequent disengagement of the pawl t and of the valve for advancing the piston c . As long as there are furnished cartridges into the trough N all these operations are repeated automatically until by reversing the hand-lever m in proper time the valve l is closed, whereupon the recoiled gun rests in the loading position, the cartridge-trough N being in its lowered position, as shown in Fig. 1, representing the starting position.

Some features of my invention which are herein shown and described are also contained in my applications for United States Patent filed January 7, 1897, and May 28, 1898, Serial Nos. 618,253 and 682,063, respectively, and are there claimed.

I claim—

1. An automatic gun comprising a carriage, a support pivoted thereto, a gun proper carried by said support, a recoil-cylinder having a plunger operatively connected with said support, a loading-cylinder having a loading-plunger working therein, a loading device

connected operatively with the said second plunger, and mechanism for governing the operation of said plungers. 70

2. An automatic gun comprising a carriage, a support pivoted thereto, a gun proper carried by said support, two cylinders and a collecting-chamber having a check-valved communication with one cylinder and an independent connection with each cylinder, a valve controlling said independent connection, a starting-lever for operating said valve, a plunger operatively connected with the swinging gun-support and working in that cylinder which has a check-valved communication with the collecting-chamber, another plunger working in the other cylinder, and a loading device operatively connected with the said second plunger. 85

3. An automatic gun comprising a carriage, a support pivoted thereto, a gun proper carried by said support, two cylinders having a valved connecting-channel, a collecting-chamber having a check-valved communication with one cylinder, an independent channel extending from the collecting-chamber to each of the cylinders, a valve controlling said independent channel, a starting-lever for operating said valve, a plunger operatively connected with the swinging gun-support and working in that cylinder which has a check-valved communication with the collecting-chamber, another plunger working in the other cylinder, and a loading device operatively connected with the said second plunger. 90

4. An automatic gun comprising a carriage, a support pivoted thereto, a gun proper carried by said support, a recoil-cylinder having a plunger operatively connected with said support and provided with a projection, another cylinder having a plunger extending into the path of said projection to be operated thereby, a loading device connected operatively with the said second plunger, and mechanism for causing the operation of said plungers. 105

5. An automatic gun comprising a carriage, a support pivoted thereto, a gun proper carried by said support, a recoil-cylinder having a plunger operatively connected with said support, another cylinder having a plunger, a loading device connected operatively with the said second plunger, a pawl for locking the gun-support in the loading position, means, connected operatively with the loading mechanism for actuating said pawl to release the gun-support, and mechanism for governing the action of the plungers. 115

6. The combination with the gun having a stop at the breech, of a movable breech block or closure, a movable cartridge-retainer carried by said closure and adapted to engage the cartridge to prevent its accidental displacement after loading, a catch for normally holding said cartridge-retainer in an inactive position, and a loading device having means for operating said catch to release the cartridge-retainer, the latter being adapted to 120

engage the stop at the breech of the gun, to move the cartridge-retainer back into locking engagement with its catch.

7. A gun comprising a carriage, a support pivoted thereto, a gun proper carried by said support having pointing-trunnions, pointing-plates, pivoted to the carriage and provided with longitudinal guides engaged by the pointing-trunnions of the gun the pivots of the pointing-plates alining with a portion of the corresponding longitudinal guides, so that the pointing-trunnions of the gun are capable of alining with the pivots of the pointing-plates, and means for actuating said plates.

15 8. In an automatic gun, the combination of the carriage, the support movably mounted thereon, the gun carried thereby, the pawl mounted on the carriage and adapted to lock the support in the loading position, the recoil-plunger connected with said support, the loading mechanism, and means, operatively connected with the loading mechanism, for throwing the pawl to release the gun-support on the completion of the loading operation.

25 9. The combination of the carriage, the support movably mounted thereon, the gun carried by said support, the recoil-cylinder on the carriage, the recoil-piston connected with the gun-support, a pawl located on the car-

riage and in locking engagement with the support when the gun is held in the recoil position during the loading operation, a loading mechanism, a loading-cylinder having a port through which the recoil-pressure is conveyed thereto, a loading-piston operatively connected with the loading mechanism, the latter engaging the pawl to trip it when the loading is completed, whereby the gun is released and then run into battery by said recoil-piston.

30 10. The combination of a pivoted gun, a pointing-plate pivotally mounted adjacent to the gun and having a slideway receiving a part of the gun, whereby to point the gun by the movement of the pointing-plate, the pivot of the latter alining with a portion of said slideway so that the said part of the gun can be brought into alinement with the pivot of the pointing-plate, and means for driving the pointing-plate around its pivot.

35 40 45 50 In witness whereof I have hereunto signed my name in the presence of two subscribing witnesses.

CONSTANTIN VON HANNEKEN.
